UNITED STATES PATENT OFFICE

LEON SAVIES, OF BILLANCOURT, FRANCE, ASSIGNOR TO LOUIS RENAULT, OF BILLANCOURT, FRANCE

WINDSHIELD

Application filed October 1, 1927, Serial No. 223,462, and in France October 16, 1926.

My invention relates to a means of attachment, the chief application of which is for attaching the back windscreens to the bodies of self-propelled vehicles.

With back windscreens as customarily used, the frames located to right or left must be folded down towards the axis of the vehicle in order to allow of access to the rear seats.

The means of attachment, which is the subject of my present invention, allows of attaching the windscreens to the sides of the car body by means of an elastic system, thus avoiding noise when travelling or the effect of car vibrations on the windscreens. This means of attachment is substantially constituted by an india-rubber ring attached for example to the window frame and which in the closed position is located in a corresponding cavity in the car body, the india-rubber ring being distorted when required so as to press against the inner surface of the cavity.

My invention also comprises certain details, which will be described at length hereinafter.

In the accompanying drawings Fig. 1 is a view partly in section of one construction of the means of attachment according to my invention; Figs. 2 and 3 show modified constructions; Figs. 4, 5 and 6 are detailed views of the apparatus shown in Fig. 3.

On reference to the drawings it is seen that the means of attachment shown in Fig. 1 comprises a spindle 1, attached to the frame of one of the jointed panels of the windscreens 2, which it is desired to attach to the sides of the car body. For this purpose there is fixed to said sides an arm 3 terminating at its upper end in a cylindrical collar 4, intended to receive an india-rubber ring 5 carried on the spindle 1 attached to the windscreens 2. The india-rubber ring is carried free on the spindle 1 between two

washers 6 and 7 slipped over this spindle. The washer 7 moreover can slide on the spindle so as to compress the india-rubber ring 5 under the action of operative means. The effect of such compression exerted upon the

collar 4, is to distort it at the moment of closing, and to cause it to press against the inner surface of the collar 4, thus securing the connection of the arm 3 to the frame of the windscreens 2. In the construction shown in Fig. 1 the operative means, which produces the distortion of the india-rubber ring 5, consists of a lever 8, ending in a fork 9 and attached by means of a pivot 10 to the end of the spindle 1. The fork 9 is constructed with an eccentric portion 11, which constitutes a cam, and which, on rotation being imparted to the lever 8, operates upon the washer 7 so as to shift it towards the left (Fig. 1) by compressing the india-rubber ring 5, which then as aforesaid, presses against the inner surface of the collar 4. The fork has also a flat 12 adjacent to the cam surface 11, which allows of its being maintained in the position shown dotted, in line with the spindle 1, when it is wished to disengage the latter from the collar 4.

Fig. 2 shows a modification, in which the india-rubber ring 5 is carried as before on the spindle 1, attached to the frame of the windscreens 2, said spindle having a head 13, whilst its other end towards the outside of the vehicle is threaded so as to take a wing-nut 14 for example. The spindle 1 is fitted in such way as to slide freely through the lower part of the frame 2 and for this purpose there is provided a groove 15, which co-operates with a set-screw 16 inserted in the lower part of the frame 2.

It is clear that when a rotary movement is imparted to the wing-nut 14, the threaded spindle 1, which is prevented from rotating owing to its groove being held by the set screw 16, shifts longitudinally towards the outside of the vehicle thus compressing the india-rubber ring 5 by its head 13, the said ring being thus distorted and pressed against the inner surface of the collar 4.

A further modification is shown in Figs. 3, 4, 5 and 6, wherein the operating lever 8 is carried by a spindle 17 located in a casing 18. On the spindle 17 is fixed an eccentric disc 19, on the periphery of which there is provided free a strap 20 attached to the spindle 1, and provided at its end outside the vehicle

with a plug 21 screwed on the end of the spindle 1 and having a shoulder resting against the india-rubber ring 5. The india-rubber ring 5 can press against the inner surface of the collar 4 supported in the aforesaid way by the attachment arm 3. It will be noticed that the inner surface of the collar 4 is shown slightly conical at 4' so as to secure a better grip by the india-rubber ring 5. The operation of the apparatus is at once apparent; it is sufficient in order to cause the release and locking of the means of attachment, to make the lever 8 rotate through 180° so as to bring about the rotation of the eccentric 19, which, when the apparatus is released, exerts a thrust on the spindle 1. It follows that for locking the apparatus the rotation of the lever 8, by shifting the eccentric 19, exerts a traction on the spindle 1 in such way that the shoulder provided on the plug 21 compresses the india-rubber ring 5 inside the conical hole 4' of the collar 4, thus securing the clamping of the two members to be united. The shifting of the lever 8 is limited by a stop 22 on the casing 18.

It will be noticed that this resilient means of support of the windscreens on the sides of the car body prevents all vibration and noise, and offers many advantages over the means hitherto employed.

It should also be noted that the means of attachment in question might be employed for other applications than the fixing of windscreens on the sides of car bodies. Thus for example it might be applied with advantage for attaching hooks or as a door-closing device.

In the several constructions above described the connecting spindle, which carries the india-rubber ring is located on the windscreen, whilst the collar is attached to the car body. It is obvious that a converse arrangement might be adopted in certain cases without departing from the scope of the invention.

Claims:

1. Means for attaching windshields to car bodies, including a support, a collar mounted on said support, a spindle extending through said collar and connected to the windshield, an elastic ring encircling the spindle and located in said collar, and means for imposing pressure upon the outer face of said ring whereby to cause the latter to exert pressure against said windshield, said means comprising a lever secured to the outer end of said spindle, and a cam carried by said lever and provided with an eccentric portion, substantially as described.

2. Means for attaching windshields to car bodies, including a support, a collar carried by the support, a spindle extending laterally through the collar and secured to the windshield, a compressible ring mounted within the collar and extending around said spindle,

a washer member mounted on the spindle on each side of the ring, and means for imposing pressure upon one washer whereby to compress said ring, said means comprising a lever having an eccentric portion and a flat portion, said portions being adapted to be alternately brought into contact with said washer in the varied movements of said lever.

In testimony whereof I affix my signature.

LEON SAIVES.
